CLAIM

The ornamental design for a toy house as shown and described.

DESCRIPTION

The file of this patent contains at least one drawing executed in color. Copies of this patent with color drawings will be provided by the Office upon request and payment of the necessary fee.

FIG. 1 is a perspective view of the front, top, and left side a toy house showing my new design;

FIG. 2 is a perspective view of the rear, top, and right side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a first reference perspective view thereof;

FIG. 10 is a second reference perspective view;

FIG. 11 is a reference front view thereof; and,

FIG. 12 is a reference rear view thereof.

The red tinted areas in FIGS. 9, 10, 11, and 12 are transparent.
